UNITED STATES PATENT OFFICE.

CAID H. PECK, OF WAVERLY, NEW YORK, ASSIGNOR TO INGERSOLL-RAND COMPANY,
OF JERSEY CITY, NEW JERSEY, A CORPORATION OF NEW JERSEY.

SQUEEZE RIVETER.

Application filed February 15, 1927. Serial No. 168,363.

This invention relates to riveting devices, but more particularly to a squeeze riveter in which the rivet sets or dies are disposed in relatively moving jaws adapted to be actuated by suitable levers to which they may be secured. Preferably, one of the levers is secured in fixed position and the other lever pivoted thereto, suitable pressure responsive devices being provided for actuating the movable lever.

The object of the invention is to produce a mechanism which will both hold the rivet in the work and also set the rivet.

Other objects will appear hereinafter, and to all of these ends the invention consists of the combination of elements and arrangement of parts substantially as hereinafter described and claimed and illustrated in the accompanying drawings, in which

Figure 1 is a longitudinal sectional elevation of a riveter constructed in accordance with the practice of the invention,

Figure 2 is a transverse elevation taken through Figure 1 on the line 2-2 looking in the direction indicated by the arrows, and

Figure 3 is a transverse view taken through Figure 1 on the line 3-3 looking in the direction indicated by the arrows.

Referring to the drawings, the invention comprises a cylinder A having an integral lateral guard B. Within the cylinder A is disposed a piston C intended to be exposed only at one end to pressure fluid. Such pressure fluid may be conveyed to the cylinder through a passage D leading through the cylinder to communicate with a passage E in a handle F. The handle F in this instance also has another passage G to which pressure fluid may be conveyed directly from a suitable source of supply (not shown) by any suitable means. The passages E and G are separated by a wall H having a port J to afford communication between the said passages E and G. The port J is controlled by a throttle valve K which may seat on a tapered valve seat L at the end of the port J adjacent the passage G.

In addition to the function of controlling the admission of pressure fluid to the cylinder A, the throttle valve K also controls the exhaust of pressure fluid from the cylinder. To this end the throttle valve is provided with a stem O carrying at its outer end a head P to control the outlet opening

Q of a port R in the handle F. The stem O may be relieved in any suitable manner to establish communication between the passage E and the atmosphere when the throttle valve K is closed. In the present instance, longitudinal grooves S are formed on the stem between the valve K and the head P for that purpose.

A means for unseating the throttle valve K is provided in the form of a lever T pivoted on a pin U which extends through the handle F, and a pin V also extending through the handle F cooperates with a lip or extension W on the lever T for holding the lever T in proximity with the stem O of the throttle valve K. A spring X acting against the throttle valve K holds said valve firmly on the seat L and also serves to close said throttle valve after the lever T has been released by the operator.

At the upper end of the cylinder is secured a lever Y by means of suitable bolts or pins Z. The lever Y is preferably secured fixedly to the cylinder and is provided at its outer or free end with a jaw b which has an aperture c to receive a holding die d which may be of any suitable form to receive the head of a rivet e.

At the juncture of the jaw b and the body portion of the lever Y is disposed a pivot pin f to act as a pivot for a movable or oscillatory lever g. The lever g is thus adapted to oscillate with respect to the lever Y and, like the lever Y, also has a jaw b which carries a setting die h. The setting die in this instance is provided with a suitable conical projection j intended to project into the rivet e for spreading the shell portion of the rivet against the work, such as the plates k.

The body portion o of the lever g is preferably of a length to enable its inner end to extend substantially to the center of the cylinder A. The inner end of the lever g is provided with a pin p on which is pivoted a connecting rod q which connects the lever g with the piston C, the opposite end of the connecting rod q being pivotally connected to the piston C by means of a wrist pin r.

Suitable means are provided for retracting the piston C after the pressure fluid has been exhausted from the cylinder A. To that end a pair of springs s are interposed between the piston and a spring plate t

preferably seated on the lever Y in order that they may be readily accessible for the purpose of inspection and replacement. In order to prevent the springs s from deflecting when they are depressed, guide pins u are riveted to the spring plate t to guide one end of the said springs. The opposite ends of the springs s are suitably guided by tubular guides v, the bores of which are of a diameter to enable the guide pins u to project therein when the piston is actuated to close the jaws b.

In the operation of the device, after the rivet e has been placed in position in the work or plates k, the riveter may be placed in such position with respect to the rivet that the holding die d will abut the head of the rivet. With the riveter in this position, the die h will be approximately in the correct position to permit the projection j to enter the aperture in the rivet u. If then the throttle valve is opened the pressure fluid flowing into the cylinder A will actuate the piston C in the direction of the stationary lever Y, thus forcing the projection j into the rivet and spreading or setting the rivet against the work.

After the rivet has been set, the throttle lever T may be released, thus enabling the spring X to close the throttle valve K and

at the same time to place the cylinder A in communication with the atmosphere through the passages D and E and the grooves R in the throttle valve stem O.

Immediately upon the exhaust of pressure fluid from the cylinder, the spring s will retract the piston C, thus opening the jaws b in readiness for the succeeding operation.

I claim:

A squeeze riveter, comprising a cylinder, a piston in the cylinder, a lever secured to one end of the cylinder, a movable lever, means pivotally connecting the levers near their outer ends, riveting dies carried by the outer ends of the levers, a connecting rod pivotally connecting the movable lever to the piston, a throttle valve controlling the admission of pressure fluid to the cylinder for actuating the piston in one direction, said throttle valve also controlling the exhaust of pressure fluid from the cylinder, a spring plate, guides on the spring plate and the piston, and springs on the guides moving the piston in the opposite direction upon the exhaust of pressure fluid from the cylinder.

In testimony whereof I have signed this specification.

CAID H. PECK.
